Inventor
Andrew G. Pappadakis
By George G. Gray
Atty.

UNITED STATES PATENT OFFICE.

ANDRU G. PAPPADAKIS, OF DETROIT, MICHIGAN.

ALARM MECHANISM.

Application filed February 26, 1923. Serial No. 621,328.

To all whom it may concern:

Be it known that I, ANDRU G. PAPPADAKIS, a citizen of the United States, residing at Detroit, in the county of Wayne and State 5 of Michigan, have invented certain new and useful Improvements in Alarm Mechanisms, of which the following is a specification, reference being had to the accompanying drawings.

10 This invention relates to alarm mechanisms and it is one of the objects thereof to provide a mechanism that will sound an alarm when the door knob is rotated, and to provide means whereby this mechanism 15 may be disconnected so that the knob may rotate without sounding the alarm if desired.

Among other aims and objects of the invention may be recited the provision of a 20 device of the character mentioned, with a view to compactness, and in which the number of parts are few, the construction simple, the cost of production small, and efficiency and operation high.

25 The improvements in the details and arrangement of parts will be apparent from an inspection of the accompanying drawings, in connection with the description hereinafter contained, and wherein a preferred 30 embodiment of the invention is disclosed for the purpose of imparting an understanding of the same.

In the drawings, wherein like characters 35 of reference indicate corresponding parts in the several views;

Figure 1 is an elevation of my improved device with a portion of the mechanism broken away; and

Figure 2 is a fragmentary plan view there- 40 of.

Referring to the drawings, 10 designates a portion of the door, 11 the escutcheon plate upon one side thereof, 12 the escutcheon plate upon the opposite side, 13 the 45 knob spindle which is substantially rectangular in cross section, as is usual, although not necessarily limited to such shape, 14 and 15 the door knobs, and 16 the latch shown herein as having two bars 17 connected therewith and tail pieces 18 upon the inner ends thereof.

The latch is normally moved outwardly by the coil springs 19, which surround the bars 17 and at their inner ends abut against 50 a plate 20 held against movement in one

direction by the lugs 21, usually integral with the lock case.

My invention contemplates the use of a bell 22 or similar device, which is shown herein as mounted upon a plate 23 slidably mounted within the lugs 24 fixed to either one of the escutcheon plates, as shown in the drawings, and within a recess 25 in the door 10, or it may be mounted in the lock or latch case with which the knob spindle 60 is connected, or in any other convenient manner.

The bell 22 is of a conventional type and requires no further description herein, being operated through a pinion 26 mounted 70 upon a spindle 27 journaled in the plate 23 and having a gear 28 which meshes into a pinion 29 on the post supporting the bell. All of this mechanism, that is, the bell and the pinion, gear, etc., are mounted upon 75 the plate 23 so as to be moved as a unit therewith by means of the button 30 that passes through a slot 31 in the escutcheon plate 12 and fixed at its inner end to the plate 23. A plate 32 associated with the 80 button 30 conceals the slot 31 irrespective of the position of the button 30 relative thereto.

The latch 16 is drawn in manually in the usual manner by means of the hub 33 mounted upon the spindle 13, the fingers 34 thereon engaging the tail piece 18 for that purpose. This latch, and the mechanism for actuating the same, is only one of many 85 forms that are in use and constitutes no part 90 of my present invention.

Connected with the hub 33 is a sector 35, the teeth of which mesh into those of the pinion 26 when the latter is moved into operative position through the manipulation 95 of the button 30. When so engaged the pinion 18 is actuated through the sector 35 so that rotation of the knobs 14 and 15 even to a very limited degree imparts rotary movement to the sector 35 and through it 100 the bell mechanism is actuated, thus sounding the alarm.

If it is not desired that an alarm should be sounded the plate 23 and all of its associated mechanism, through the manipulation of the button 30, is moved so that the teeth of the pinion 26 are out of engagement with those of the sector 35, thus the knob may be rotated at will without actuating the alarm mechanism. In some knob 105 110

mechanisms one of the knobs may be rotated without imparting motion to the other, in which case the sector 35 may be directly associated with either one of them, so that the 5 rotation of one knob only will sound the alarm. The plate 23 is held in its extreme position by the spring 36 that is secured at one end by a screw 37 and which enters either one of the notches 38 and 39 depend- 10 ing upon the relative position of the plate. The spring engages the notch 38 when the alarm mechanism is in position to be sounded by the rotation of the knob and the notch 39 when it is out of the path of move- 15 ment of the sector 35.

There are minor changes and alterations that may be made within my invention, and I would therefore have it understood that I do not limit myself to the exact construction herein described, but claim all that 20 falls fairly within the spirit and scope of the appended claim.

Having described my invention, what I claim as new and desire to secure by Letters Patent, is:—

In a device of the character described, the combination with an escutcheon plate having a plurality of lugs upon the inside thereof; a plate slidably mounted between said lugs; an alarm mechanism connected with the inside of said plate so as to be moved therewith, the source of power for operation thereof being through a pinion; a knob spindle rotatably mounted in said escutcheon plate; a sector on said spindle; and means exterior to said escutcheon plate having connection with said plate for moving the same toward and away from said spindle and said pinion into and out of engagement with said sector plate.

In testimony whereof, I have hereunto affixed my signature.

ANDRU G. PAPPADAKIS.
